TAPE DISPENSER OR THE LIKE

Leo F. Wildgen, Minneapolis, Minn., assignor to Arthur Salm Inc., Chicago, Ill., a corporation of Illinois

Application May 11, 1959, Serial No. 55,877

Term of patent 14 years

Claims priority, application Germany March 21, 1959

(Cl. D74—1)

Fig. 1.

Fig. 2.

Fig. 3.

Fig. 4.

*Fig. 5.**Fig. 6.**Fig. 7.*Fig. 1 is a perspective view of a tape dispenser showing my new design;

Fig. 2 is an end view of the tape dispenser of Fig. 1 showing the cutter in its normal position;

Fig. 3 is a bottom view of the tape dispenser of Fig. 1;

Fig. 4 is an end view of the tape dispenser of Fig. 1 showing the opposite end thereof;

Fig. 5 is a top plan view of the tape dispenser of Fig. 1;

Fig. 6 is a side view of the tape dispenser of Fig. 1; and

Fig. 7 is a side view of the tape dispenser of Fig. 1 with the cutter in the actuated position.

The length of tape shown in broken lines in Fig. 7 is for illustrative purposes only.

I claim:

The ornamental design for a tape dispenser or the like, substantially as shown and described.
